METHOD OF IMPREGNATING STAKES,
POSTS, POLES, AND THE LIKEWalter Ludwig, Konigsberg, Germany, assignor
of one-half to the firm of Ostpreussen-werk
Aktiengesellschaft, Konigsberg, GermanyApplication February 16, 1937, Serial No. 126,049

4 Claims. (Cl. 21—24)

When impregnating wooden stakes, posts, poles and the like, the impregnating agent has hitherto been introduced from the peripheral surface to the core, or, if the member contained an axial passage, it was introduced from the passage radially outwardly, or the impregnating agent was forced into the wood at one end until it appeared at the other end.

In the first of the above mentioned procedures 10 the impregnating agent oftentimes does not penetrate the sap wood sufficiently, that is, it may not go entirely to the core. In that case the wood around the core which is partially impregnated, or not impregnated at all, is subject to rot, which 15 of course is extremely detrimental to the wood. This is particularly dangerous because the condition of the wood cannot be perceived from the outside.

If the posts are hollow or otherwise provided 20 with an axial passage, the impregnating agent passes radially outward from the passage, and in this case it sometimes happens that the outermost portions of the sap wood are not sufficiently impregnated. It appears from the above facts that 25 impregnating methods in which the impregnating agent passes radially through the wood are unsatisfactory in that the wood is insufficiently impregnated either at the outer portions of the sap wood or in the inner portions near the core. 30 This condition can be improved slightly if the wood, prior to applying the impregnating agent, has had the air removed before incorporating the impregnating liquid under high pressure. Axial impregnation can be carried out only with sap- 35 fresh wood, that is, wood having bark and bast. The impregnating agent is introduced through the end grain, generally from the top end of the trunk, and it is necessary to displace the sap with impregnating liquid in order to place the wood 40 in proper condition to retain the impregnating liquid.

In this method the impregnating liquid is distributed so that the greatest amount of it is found at that end of the wood at which it was introduced, and a smaller amount at the opposite end. This is the case, at least as long as it takes 45 for the impregnating liquid to fully saturate the colloidal wood, at which time the distribution of the liquid becomes more equalized. This state is 50 attainable, however, only after a long time, within which a certain portion of the impregnating agent may be lost. Impregnation is generally discontinued when the ratio between the two ends of the wood has become about 0.5 or 0.66:1. If 55 the impregnating liquid contains substances re-

tained or absorbed in the wood, the state of unequal distribution is particularly perceptible.

Apart from the impregnation in an axial direction, the distribution of impregnating liquid is not uniform radially, or in a transverse sectional area. When an impregnating liquid is applied at the end of a trunk, it distributes itself radially only little by little, so that at first only the innermost portions of the wood are impregnated, and the outer portions near the peripheral surface of the trunk are only impregnated after a long time. The outer strata of the wood which conveys the sap is capable of conveying the impregnating liquid far better than the inner strata, in consequence of which unequal distribution of the liquid is attained in an axial direction if the impregnating procedure is not carried on long enough to equalize the distribution of the liquid. It will now be clear that the manner of displacing the sap by the impregnating liquid in an axial 20 direction results in an unequal distribution of the liquid axially as well as radially, in consequence of which the life of the wood is shortened.

In order to do away with the condition mentioned it is necessary to convert the pole, post, etc., into a body which is mushroom-proof throughout its entire mass. Poles, posts, and the like are subject to the detrimental action of mushrooms when they have been placed in the ground, and the strength of this action depends upon the 30 sort of ground in which they are placed.

In order to make the matter clear, I refer to the accompanying drawings. Figures 1, 2 and 3 are diagrams. Figure 4 is an axial section through a piece of the trunk, and Figure 5 is a 35 transverse section through the same piece, all as hereinafter fully described.

Referring to Figure 1, *a* denotes a curve disclosing the degree to which a pole placed in the ground is endangered by mushrooms, and *m* denotes the pole, the lower end *m'* of which is the portion placed in the ground. The course of the curve *a* shows that it is not economical to render the pole mushroom-proof along its entire length. It would be more economical to operate 45 in such a manner that the degree of immunity would correspond to the curve *b*, but this result could not be obtained by any of the existing methods. It can be, and is, however, obtained by means of the present improved method in 50 which the impregnating liquid is incorporated into the wood simultaneously from both ends, that is, from the top end to the bottom end and reversely at the same time. If desired thereafter, radial impregnation may also be employed, like- 55

wise in two directions opposite to each other, that is, radially outwardly and from the periphery inwardly at the same time. The impregnating liquid may therefore under such circumstances enter into the wood in four directions.

It has already been proposed to impregnate poles, posts, etc. in an axial direction in two phases, first from one end in one direction and then from the other end in the other direction, but this procedure entails considerable disadvantages. A long time is required, and the impregnating liquid introduced during the second step or phase drives back the impregnating liquid introduced during the first step or phase until the second step liquid arrives at the point where the first step liquid has been driven into the wood.

When introducing impregnating liquid simultaneously from both ends of the trunk or pole, as is done in the present improved method, the two currents of impregnating liquid do not encounter one another, so as to hinder each other, but provision is made that they leave the trunk or pole about in the middle portion of the same by passing radially outwardly, for which purpose a plurality of axially extending slots is provided, as illustrated by way of example in Figures 4 and 5. More properly, these slots may be said to extend in the direction of the fibers of the wood, as well as radially. In Figures 4 and 5, 1 denotes the trunk, and 4 denotes longitudinally or axially extending slots which are uniformly distributed about the circumference of the trunk. At the points where these slots are located, the bark and the bast are removed, and the slots extend radially from the core to the free outer surface, as shown in Figure 4, which also shows that the slots may be trapezoidal in shape, which means that their sectional area is enlarged in an outward direction. But I wish it to be understood that an enlargement of the sectional area may take place also in the circumferential direction of the trunk, as has been illustrated in Figure 5. There may be used one device or the other, or both together.

The numeral 1 in Figures 4 and 5 denotes the sap wood, whereas numeral 3 denotes the core wood. The inner length 5 of the trapezoidal slots extends along the core wood and the outer length 6 extends along the sap wood at the outer surface thereof. The bast and the bark are not shown in Figures 4 and 5. Owing to the possibility of varying the shape of the slots, or whatever other shape the openings may have, an opportunity is afforded to accommodate the working procedure to the kind of wood and to the inner structure thereof, as well as to the height of the fall of the impregnating liquid from the receptacle containing it, it being understood that this receptacle is located at a certain height above the pole or trunk, which lies horizontal while being subjected to the impregnating operation.

When the impregnation is carried out with the pole or trunk 1 lying horizontal, and a receptacle containing the impregnating liquid arranged sufficiently high above it, the fall is utilized in both halves of the trunk, in opposite directions, and the length of time necessary for complete impregnation is only about half the time necessary to cause the liquid to penetrate the wood from one end to the other, and reversely, in two stages. Also, the amount of impregnating liquid used is only half as much, since the amount of this liquid used in the first stage of the reverse end process is a loss, because the liquid used in the second stage drives it out, as has already been

described in a preceding part of the specification. The method of introducing or incorporating the impregnating liquid at the same time at both ends of the trunk or pole so as to produce two currents flowing toward each other presents the following advantages:

(a) The entire amount of the impregnating agent employed is distributed economically along the length of the pole in proportion to the danger from mushrooms in such a manner that at the ends of the poles which are most endangered the largest amount of the impregnating agent is present, and in the middle portion, where there is the least danger, the smallest amount of the agent is present. The distribution is then such a one as indicated by the dotted line or ideal curve b in Figure 1. In other words, the most perfect and most economical utilization of the impregnating agent is attained by employing my improved method.

(b) In the case of poles, employed for carrying high voltage wires, ordinarily the current must be turned off while the pole is being impregnated or covered. This can be obviated by means of the present invention which renders it possible to expose the poles either to the long action of a normal protective solution, or to a comparatively short action of a stronger solution.

(c) The simultaneous impregnation in two directions counter to one another entails no difficulty whatever as only one elevated receptacle for the impregnating liquid need be used, and nothing else is required but separate pipes to conduct the liquid to each end of the trunk.

(d) The method is applicable to all sap-fresh types of wood with bast and bark.

(e) Those portions of the wood which contain the smallest amount of the protective substance always lie at or near the peripheral surface of the trunk, and this being so, those portions can be easily examined after the bast and bark have been removed so that it is possible to apply any additional measure if suitable to the purpose.

Counter to the effect of the axial introduction or incorporation of the protective substance from both ends and at the same time, all other methods in which the protective substance is applied at the periphery of the trunk so as to introduce it inwardly from the peripheral surface causes greater density of the substance at the periphery so that insufficiently impregnated portions of the wood are invisible and inaccessible. But, if the wood is treated first axially in the manner described and then inwardly from the peripheral surface, then impregnation is not objectionable, in that no portions of the wood are insufficiently impregnated. Normally the impregnation in this manner, that is, radially outwardly and inwardly from the peripheral surface, must be carried out in two work phases.

The impregnation radially outwardly is due to the axial impregnation which takes place not only axially but also laterally, or radially outwardly, there being attained in the wood a fall of impregnating liquid in two directions at right angles to each other. As the impregnation is effected axially as well as radially and in two directions, always counter to one another, there are consequently four ways in which the impregnating fluid exerts its effect. However, four working phases are not necessitated, but rather only two, of which the first effects the impregnation in the two axial directions and in the direction radially outwardly, whereas the second phase is

that in which the impregnation takes place from the peripheral surface inwardly.

I think myself to be the first who has discovered and ascertained the unequal density of the impregnating substances in the wood and in the sectional areas of the same when impregnating liquid is applied at one end of the trunk, pole, etc. I have carefully measured the hydraulic pressure in the several portions of the 5 sectional areas and have found that the pressure in the innermost portion of the sap wood is higher than in the outermost portion. Thus, there exists a fall of pressure radially outwardly which is greatest at the end of the pole where the impregnating liquid is introduced, and is 10 lowest at the opposite end, where it may even go down to zero. The greater the fall of pressure in the wood in a radial direction of the sectional area, the more uniform is the distribution of the 15 impregnating substances over the sectional area of the wood, but it is better at the end of the pole to which the liquid was applied than it is at the opposite end.

In the practical application of the present 20 improved method, packing or tightening rings are applied to the ends of the trunk or pole, etc. The breadth of these rings can be varied according to the requirements, and also the sectional area of the openings or passages in the 25 middle portion of the trunk can be varied and adjusted to the height of the fall of the liquid from the receptacle to the ends of the trunk. It is thus rendered possible to provide for a uniform distribution of the impregnating agent 30 along the entire length of the trunk, as well as in the sectional areas of the same.

The fall in the longitudinal direction of the trunk will appear from Figures 2 and 3, in which, in the one case large lateral or radial passages, 35 and in the other case small openings or passages, are assumed to exist. Referring to these figures: L denotes the length of the trunk; H denotes the pressure of the liquid at the exit end, that is, at the orifice of the radial passages; S denotes the height of the level of the impregnating liquid 40 in the elevated receptacle; O denotes one of the exit openings, which is assumed to be large in Figure 2 and small in Figure 3. In both cases this opening lies about in the middle of the trunk. The line *gi* indicates the course of the fall in the innermost portion of the sap wood, and a line *ga* indicates the course of the fall in the outermost portion of said wood. The letter 45 *r* indicates the radial fall.

The axial supply of the impregnating liquid in 50 two directions counter to one another in connection with the provision of the tightening rings at the two ends of the trunk or pole constitutes not only a longitudinal incorporation of 55 impregnating agent into the wood, but also a radial incorporation in the outward direction, whereby the impregnation is rendered excellently uniform over the entire sectional area of the trunk, this being especially true of the sap wood 60 along the entire length of the trunk, and being further true if the duration of the impregnation 65 procedure is restricted to a certain moderate period.

When a sap-fresh wood trunk is treated first in 70 an axial direction, that is to say, in both axial directions counter to one another, and if that trunk is then treated in the direction from the outer surface of the trunk to the core thereof, faults which might possibly occur in the older 75 methods are completely obviated, which is an-

other important advantage of my improved method.

The radial incorporation of an impregnating or protecting substance may also be effected, in the case of a sap-fresh trunk, by applying to 5 the outer surface of the trunk, after the bast and bark have been removed therefrom, a salt solution which then penetrates into the wood by diffusion. It is then advisable to protect the 10 thus treated surface from rain during the time 10 in which the salt solution is to act, possibly by a sort of roof over the trunk. The length of time necessary to carry out this operation is considerably shorter than if an osmotic procedure is 15 used.

It is likewise possible to let the axially impregnated trunk dry and impregnate it thereafter in a boiler under pressure with a salt solution or with tar-oil, provided that the sort of 20 wood under treatment permits of such a procedure. If the protection procedure is carried out in this manner, that is, by the employment of a boiler and of pressure, after first being subjected to the axial impregnation procedure, the 25 two procedures supplement each other, in that the salt solution or the tar-oil enters into the cell walls and forms there, if the substance used is of a suitable kind, compounds which are only with difficulty soluble in water, and remain in place if the wood becomes wet. In the case of a 30 tar-oil, this substance repels the water and exerts a particularly useful effect in that it prevents the formation of mushrooms. When the wood is exposed to wetness, for a long time, the tar-oil passes from the cell walls into the cell 35 cavities and exerts therein, in combination with the salt, a chemical-biological action, as well as a physical one, this latter effect being due to the water repelling action of said oil.

I claim:

1. A process for the impregnation of fresh, 40 sappy, wood poles, masts or timbers comprising providing air openings near the center of the length thereof and extending substantially completely through the sap wood, then simultaneously forcing impregnating fluid into each end of the pole, driving the sap of the pole out of said openings ahead of said fluid and continuing the introduction of said fluid until it passes out of 45 said openings.

2. The process as specified in claim 1, particularly as applied to electric poles and the like, further comprising the provision in the member to be treated about equally remote from the ends thereof a plurality of radial slot-like passages 50 extending in the direction of the fibers and from the outer surface into the interior of said member.

3. The process as set forth in claim 1 further comprising the provision in the member to be 55 treated about equally remote from the ends thereof a plurality of passages extending in the direction of the fibers and from the surface of the member radially into the interior thereof as far as the core wood, and substantially equally 60 distributed about the circumference of the same, in such a manner that each of said passages has substantially the shape of a trapezoid, the short base of which is parallel to the axis of the member and lies in the heart wood while the long 65 base is at the periphery of the sap wood.

4. A process for the impregnation of fresh, 70 sappy, wood poles for the support of electric wires comprising providing openings near the center of the length thereof and extending sub- 75

stantially radially and completely through the sap wood, then simultaneously forcing impregnating fluid into substantially the whole sap wood area of each end of the pole, driving the sap of the pole out of said openings ahead of said fluid, continuing the introduction of said

fluid until it passes out of said openings and controlling the pressure serving to distribute the fluid radially in the pole by regulating the number and size of said openings.

WALTER LUDWIG.
